ADVERTISING NOVELTY

Samuel Schweitzer, Shaker Heights, Ohio

Application December 12, 1941, Serial No. 422,685

3 Claims. (Cl. 40—126)

This invention relates to advertising means and particularly to small toy-like devices which may be used to arouse and stimulate interest in some article of commerce.

The primary object of the invention is to provide an attractive balancing toy which may be associated with a particular commodity and which has space thereon for advertising the same.

Another object is to construct a device of the type mentioned out of inexpensive materials and which may be quickly and easily applied to the article to be advertised or the container thereof without disturbance or annoying loss of time.

Further object is to construct such device so that it may become animated or to move in a manner which automatically discloses the advertising indicia thereon.

These and other objects and features of the invention will become apparent from a study of the following description and claims together with the accompanying drawing in which like parts are designated by like reference characters and wherein:

Figure I is a perspective view of the device mounted on a conventional beverage glass;

Figure II is a plan view of the device particularly illustrating how the decorative design thereof harmonizes with the material used in its structure;

Figure III is a front view of the device made ready to apply;

Figure IV is a side view thereof;

Figure V is a cross-sectional view thereof taken along the line and in the direction of the arrows 5—5 of the Figure II;

Figure VI is a view of a modified form of the device; and

Figure VII is a side view thereof.

In the drawing, there is shown a conventional glass 11 containing a liquor or beverage 12 and which glass has a lip or brim portion 13 thereon. Mounted on the brim 13 is a stiff piece of paper 20 which is blanked in substantially a V-shaped form. The paper may be of an inexpensive kind such as ordinary letter-writing paper. Its only requirement is that it be light in weight and stiff enough to retain its normal shape. The arms 22 which digress and form a V-shaped pattern may be of almost any ornamental configuration. As, for example, the device shown in the drawing resembles a butterfly. The portion between the diverging arms 22 is referred to herein as the notch portion and is indicated in the drawing by the character 23. The general shape of the

V-shaped design should be such that when it is mounted on the glass 11 as in Figure I, the arms 22 are noticeably spaced from the brim, are tangential thereto and do not touch the glass in any manner whatsoever.

Integral with or attached to the notch portion 23 is a small tab 24 which is easy to turn down as in the Figures III and IV and made to engage the brim of the glass as in Figure I.

10 Mounted on the forward or extreme ends of the arms 22 are small weights 25. These may take any shape or form and may be simply glued to one side of the paper or affixed thereto as shown in the drawing. As illustrated, the weights 25 consist of small nickel plated rivets which are applied to the paper as shown in the Figures III, IV and V. The rivets, however, should be of such material, color and size that become noticeable for their decorative effect rather than for their functional use. They should be of a kind that may be easily and quickly applied and should blend with and substantially complete the incomplete ornamental design 21 imprinted on the top of the device. In the drawing, for example, the ornamental design of the butterfly wings utilizes the two weights 25 as shown for its completion.

15 The main V-shaped body portions 20 and the tabs 24 may be die-cut in one operation. When used or applied to the glass, the tab 24 is simply turned down so that it depends at right angles thereto and is gently hooked on to the brim of the glass. In this way, the exact center of gravity of the device may be easily and quickly placed on the brim portion 13.

20 The shape of the body and the two weights 25 should be of such proportions and size that when mounted on the glass, the two weights 25 balance the portion of the body below or to the rear of the tab portion 24, and the weights should be so distributed that the assembled device will normally rest horizontally on the brim of the glass of its own accord as shown.

25 Each device has certain advertising indicia printed on the bottom surface thereof and which indicia are indicated by the character 29 in the drawing. The advertising indicia 29 should, to be most effective, be of a type that naturally harmonizes with the device itself or its capabilities or its movements. For example, the advertising indicia 29 in the drawing shows the words "drink the balance blend" and the device itself is capable of being balanced in a somewhat baffling manner.

Modified form

The modified form of the device shown in the Figures VI and VII is substantially the same as the one heretofore described. It has a body portion 20, an ornamental design 21 and advertising indicia 29 imprinted thereon, diverging arms 22, a notch portion 23 and a pair of weights 25. It differs from the preferred form in that the paper is of a liquid absorbing type, and the tab 24, instead of being short and round as shown in the Figures I and III, is long and stem-like. The stem 28 is immersed in the beverage in the glass at the same time that the device 20 is balanced on the brim 13 so that when the paper tab or stem 28 absorbs some of the liquid in the glass by capillary action, some of the liquid will seep into the portion of the body 20 rearward of the center of gravity and toward the point 26 in back of the elongated stem 28. The weight of the rear portion of the body will then become greater than the front portion and the advertising indicia 29 imprinted on the underside of the sheet will automatically and gradually become visible, the effect being that of a slowly moving butterfly.

One of the many objects of this novelty device is that is applicable to many types of commercial beverages and is relatively inexpensive to produce and use in large numbers. They may be quickly and easily applied by the waiters or hosts and do not require sensitive balancing for complete effect. The device may also be used as a coaster or support for the beverage glass when the effectiveness of the animation is gone or when its advertising function is no longer the primary value.

While the invention has been illustrated in its preferred forms and while certain general terms have been used to describe it, it is to be understood that the embodiment of the invention as described and illustrated herein is not to be considered in a limiting sense as there are many other designs, forms or modifications of the invention which are also considered to be within the scope of the appended claims.

I claim:

1. In combination with a glass and a liquid therein, an animated advertising novelty, comprising, a sheet member including diverging arms substantially tangential to the said glass and in spaced relation therewith, a tab member integral with the sheet member depending therefrom and engageable with the said glass, and a capillary stem portion on the said sheet member immersed in the said liquid and capable of being saturated thereby, the said tab and sheet members having a center of gravity in the stem portion causing the said arms to assume a horizontal position when the stem portion is unsaturated and to assume a vertical position when the stem portion is saturated with the said liquid.

5 2. In combination with a glass and a liquid therein, an animated advertising novelty, comprising, a sheet member including diverging arms substantially tangential to the said glass and in spaced relation therewith, and a capillary stem portion attached to the sheet member, engageable with the said glass, immersed in the said liquid and capable of being saturated therewith, the said sheet member having a center of gravity in the stem portion causing the said arms to assume a horizontal position when the stem portion is unsaturated and to assume a vertical position when the stem portion is saturated with the said liquid.

10 3. In combination with a glass and a liquid therein, an animated advertising novelty, comprising, a sheet member including diverging arms substantially tangential to the said glass and in spaced relation therewith, and a capillary stem portion attached to the sheet member, engageable with the said glass, immersed in the said liquid and capable of being saturated therewith, the said sheet member having a center of gravity in the stem portion causing the said arms to assume a horizontal position when the stem portion is unsaturated and to assume a vertical position when the stem portion is saturated with the said liquid.

15 4. In combination with a glass and a liquid therein, an animated advertising novelty, comprising, a sheet member including diverging arms substantially tangential to the said glass and in spaced relation therewith, the said sheet member having a decorative design imprinted on the top thereof and advertising indicia on the bottom thereof, and a capillary stem portion attached to the sheet member, engageable with the said glass, immersed in the said liquid and capable of being saturated therewith, the said member having a center of gravity in the stem portion causing the said arms to assume a horizontal position when the stem portion is unsaturated thus exposing the decorative design to normal view and to assume a vertical position when

20 5. In combination with a glass and a liquid therein, an animated advertising novelty, comprising, a sheet member including diverging arms substantially tangential to the said glass and in spaced relation therewith, the said sheet member having a decorative design imprinted on the top thereof and advertising indicia on the bottom thereof, and a capillary stem portion attached to the sheet member, engageable with the said glass, immersed in the said liquid and capable of being saturated therewith, the said member having a center of gravity in the stem portion causing the said arms to assume a horizontal position when the stem portion is unsaturated thus exposing the advertising indicia to normal view.

SAMUEL SCHWEITZER.
